DRYING ROLL

Seddon C. Nelson, Fredericksburg, Va., and Hans K. Steinfeld, Swarthmore, Pa., assignors to American Viscose Corporation, Philadelphia, Pa., a corporation of Delaware

Application August 30, 1954, Serial No. 453,062

12 Claims. (Cl. 34—124)

The present invention relates to a drying roll which may be used for drying continuously traveling sheets of material such as cellophane. In particular, the invention relates to a drying roll which when heated to drying temperature maintains a temperature differential between the end and central surface portions of the roll. In addition, the temperature differential may be adjusted as desired.

In the production of continuous paper sheets, such as cellophane, it is the general practice to dry the wet sheets by passing them over a series of rotating, hollow rolls having smooth uninterrupted surfaces and which are internally heated by hot water or steam. The surfaces of these rolls are of uniform temperature and when they are used to dry continuous cellophane sheets many difficulties and disadvantages are present which tend to produce products of inferior quality.

When drying cellophane with the uniform surface temperature rolls, it has been found that the film edge portions are dried more rapidly than the central portion of the film. As a result of such drying pattern, the edge portions of the film shrink more rapidly than the central portion of the film during normal transverse shrinkage. As a result, there occurs abnormal shrinkage adjacent the edge portions of the film whereby the finished film or sheet has curly or floppy edges and an uneven distribution of moisture across the film.

With such non-uniform drying, a strain is produced in the final film whereby the film is neither flat nor straight. A film which is not straight is one which will not lie substantially in a straight line when laid on a table. A cross section of a length of cellophane film which is not flat, if stretched between two end supports, shows a curved line instead of a straight line when laid on a table. A cross section of a length of cellophane film which is not flat, if stretched between two end supports, shows a curved line instead of a straight horizontal line. Obvious difficulties are encountered when using such a strained film in wrapping machines, bag making machines, and multi-color printing machines.

Various drying methods and apparatus have been developed in an attempt to overcome the difficulties and disadvantages mentioned above, but without much success. For example, efforts have been made to mechanically prevent the shrinkage of the film during the drying operation by clamping the film at both edges to prevent it from shrinking transversely of its direction of travel. However, it has been found that such a drying system causes tears or weak spots adjacent the edge portions of the sheet or film.

It is an object of the present invention to provide a rotatable drying roll which will uniformly dry a continuous sheet traveling thereover to produce a flat and straight resultant sheet.

It is also an object of the present invention to provide a rotatable drying roll wherein a temperature differ-

2

ential is maintained between the end and central portions of the roll surface.

It is a further object of the invention to provide a drying roll wherein the temperature differential of the roll may be adjusted as desired.

A more complete understanding of the invention may be had from a study of the description and the drawings wherein:

Figure 1 is an elevation, partially in section, of the drying roll.

Figure 2 is an enlarged view in section of a portion of one end of the roll of Figure 1.

Figure 3 is a sectional detail of another embodiment of the invention.

Figure 4 is a sectional detail of a further embodiment of the invention, and

Figure 5 is a section taken along line V, V of Figure 1.

In brief, the drying roll of the present invention is formed of a rotatable drum having two adjustable partitions within the drum ends which partitions after proper positioning may be fixed in place. Manually controlled adjusting devices are connected to the adjustable partitions for moving them back and forth within the drum, and a heating medium circulating system is provided for introducing and exhausting a suitable drum heating medium to and from the area between the partitions.

Referring now to Figure 1 of the drawing, the drying roll assembly comprises a drum section 1 having end supports 2 and 3 secured to the drum ends by bolts 4, 4 or other suitable securing means. The rotatable drying roll 1 is journaled in a suitable frame work (not shown) by positioning the drum end supports 2 and 3 within suitable frame work bearings (not shown).

As seen in Figures 1 and 5, one of the adjustable partitions 15, is positioned within the drum 1 near one end thereof hereafter termed the service end. The service end partition includes a threaded hub 16 and a web section 17 which is expanded at its periphery to form a rim 18, the outer surface of which is grooved to accommodate a resilient tubular sealing ring 19 cemented or otherwise secured therein. The ring 19 seals off the space between the partition 15 and the service end of the drum from the remainder of the drum to prevent the heating medium from entering into the sealed off area.

The sealing ring 19 has a diameter which is greater than the distance between the inner drum surface and the flange 18 so that the sealing ring is compressed to provide an adequate seal. The sealing ring 19 may be formed of a natural or a synthetic rubber such as Neoprene (registered trademark). For adjusting the position of the partition 15 within the drum 1, adjusting rod 20 is positioned within and extends from beyond the end support 3 into the drum interior and is screwed into the threaded hub 16. A ball grip 21 is affixed to the free end of the rod 20 for moving the partition 15 back and forth within the drum 1. Any suitable means such as a set screw 22 holds the rod and partition in place after the partition has been properly positioned within the drum 1. In the alternative, the rod 20 may be unscrewed from the disc 15 after the disc is properly positioned within the drum 1 and a plug placed within the end support 3 to close off the drum interior from the atmosphere.

A second adjustable partition 24 (Figure 2) is positioned within the opposite portion or drive end of the drum. The partition 24 includes hub 25, a web section 26 which is expanded at its periphery to form a rim 27, the outer surface of which is grooved to accommodate a second resilient ring 19 compressed between the rim 27 and the inner surface of the drum 1. Sleeve 29, screwed into the hub 25 of partition 24, is connected by

70

reducing coupling 30 with sleeve 31 of smaller diameter which extends through and beyond end support 2 (Figure 1). A hand grip 32 is affixed to the periphery of sleeve 31 so that the connected sleeves 31 and 29 and partition 24 may be moved toward or away from the partition 15 to increase or decrease the area between the partitions. Partition stop 33 (see Figure 2) limits the movement of adjustable partition 24 toward the end of the drum 1. A similar stop is also used to limit the movement of partition 15 with respect to end support 3. When 10 the adjustable partition 24 is positioned as desired, set screw 34 extending through end support 2 may be tightened to hold the sleeve 1 and partition 24 in position.

For supplying a heating medium such as steam or hot water to the area between the partitions a fixed feed pipe 35 extends from a point beyond the end of sleeve 31, through coupled sleeves 31 and 29, and into the area between the two partitions 15 and 24 (Figures 1 and 2). The heating medium introduced through pipe 35 is circulated within the area and exhausted therefrom through a path defined by the bores of sleeves 29 and 31 and the periphery of feed pipe 35. The sealing rings 19 prevent the heating medium from passing into the areas between the partitions and the end supports. The exhaust medium passes outwardly into the atmosphere or it may be collected as it passes beyond the end of sleeve 31 and passed to a conditioning device which will prepare the exhausted medium for use in the drum.

Figure 3 shows an embodiment of the invention for sealing off the area between the adjustable partitions and the drum ends wherein a sponge rubber strip 40 is cemented around and to the inner surface of drum 1. The thickness of strip 40 is greater than the distance between the peripheral flange 41 of the adjustable partition 42 and the inner surface of drum 1 so that the strip is compressed to provide an effective seal. The strip 40 is of sufficient length to accommodate any position of partition.

Figure 4 shows another embodiment of the invention for sealing off the area between the adjustable partitions and the drum ends wherein a sponge rubber ring 45 is clamped to the partition 46 being held in position by retaining ring 47 and bolt 48 or another suitable securing means.

From the above description, it is apparent that the portions of the roll surface near the ends of the roll will be maintained at lower temperatures than the central portions of the roll regardless of the area between the two partitions. This temperature differential is, of course, achieved because of the natural resistance of the metal from which the roll is constructed to heat conduction. The temperature will gradually decrease as the heat from the central heated surface portion is conducted from the center of the roll surface toward the surface ends thereof. When the partitions are close together, the heating medium is confined to a small central portion of the roll and the central surface portion of the roll will be maintained at a high temperature while the end surface portions will be maintained at a lower temperature than the central surface portion. When the partitions are spaced far apart, the central surface portion of the roll will then be maintained at a low temperature and the end surface portions of the roll will be maintained at still slightly lower temperature than the central surface portion.

In practice, an experimental drying run is conducted during which the partitions are constantly adjusted while the rolls are rotating until the optimum temperature differential for the roll for uniform sheet drying is achieved. The frictional contact between the resilient rings 19 and the inner drum surface is sufficient to hold the partitions in place, however if required, the set screws 22 and 34, or other suitable securing means, may be used to hold the partitions in place. After proper positioning of the partitions, the roll is ready for production usage

and no further adjustment of the partitions is made during the production run since any change in temperature differential during operation results in non-uniformity with respect to shrinkage within the sheet.

It is to be understood that changes and variations may be made without departing from the spirit and the scope of the invention as defined in the appended claims.

We claim:

1. A drying roll for drying a continuous sheet of flexible material comprising a rotatable hollow drum having a substantially smooth and uninterrupted surface over and against which the sheet travels, means for supplying a heating medium to the interior of the drum, and at least one unbroken partition mounted within and closing off one portion of the drum interior from the remaining portion of the drum interior for effecting a temperature differential between the two portions of the drum interior and the corresponding portions of the drum surface.

2. A drying roll for drying a continuous sheet of flexible material comprising a rotatable hollow drum having a substantially smooth and uninterrupted surface over and against which the sheet travels, at least one adjustable partition within the drum which is rotatable therewith for sealing off a section of the drum interior, means connected with the partition for adjusting and controlling the position of the partition within the drum interior, and means for introducing a drum heating medium into the drum interior at a point beyond the sealed-off section of the drum interior.

3. A drying roll for drying a continuous sheet of flexible material comprising a rotatable hollow drum having a substantially smooth and uninterrupted surface over and against which the sheet travels, end supports for the drum, at least one adjustable partition within the drum which is rotatable therewith for sealing off a section of the drum interior, means connected with the partition and extending externally of the drum through one of the end supports for adjusting and controlling the position of the partition within the drum interior, and means for introducing a drum heating medium into the drum interior at a point beyond the sealed off section of the drum interior.

4. A drying roll for drying a continuous sheet of flexible material comprising a rotatable hollow drum having a substantially smooth and uninterrupted surface over and against which the sheet travels, end supports for the drum, a first adjustable partition within the drum which is rotatable therewith for sealing off a section of the drum interior, a second adjustable partition within the drum which is rotatable therewith for sealing off a second section of the drum interior, means connected with one of the partitions and extending externally of the drum through one of the end supports for adjusting and controlling the position of the partition within the drum interior, and means for introducing a drum heating medium within the area between the two partitions.

5. A drying roll for a continuous sheet of flexible material comprising a rotatable hollow drum having a substantially smooth and uninterrupted surface over and against which the sheet travels, hollow end supports affixed to the drum ends, a first adjustable partition within the drum which is rotatable therewith for sealing off a section of the drum interior, a second adjustable partition within the drum which is rotatable therewith for sealing off a second section of the drum interior, means connected with the first adjustable partition and extending through one drum end support for adjusting and controlling the position of the adjustable partition within the drum interior, means connected with the second adjustable partition and extending through the opposite end support for adjusting and controlling the position of the second adjustable partition within the drum interior, and means through which a drum heating medium is introduced within the area between the two partitions.

6. A drying roll for drying a continuous flexible material sheet according to claim 5 wherein the first adjustable partition comprises a hub, a web section, a rim formed by expansion of the web section, a sealing ring of resilient material positioned around the rim, and a rod secured to the hub for moving the partition back and forth within the drum.

7. A drying roll for drying a continuously traveling sheet of flexible material according to claim 6 wherein the resilient sealing member comprises a tubular ring.

8. A drying roll for drying a continuously traveling sheet of flexible material according to claim 5 wherein the second adjustable partition comprises a hub, a web section, a rim formed by expansion of the web section, a sealing ring of resilient material positioned around the rim, a sleeve assembly secured to the rim, which sleeve assembly extends through and beyond the opposite end support, and a hand grip affixed to the free end of the sleeve for moving the partition back and forth within the drum.

9. A drying roll for drying a continuously traveling sheet of flexible material according to claim 8 wherein the resilient sealing member comprises a tubular ring.

10. A drying roll for drying a continuously traveling sheet of flexible material comprising a drum, hollow end supports for the drum, an adjustable partition within the drum which is rotatable therewith for sealing off a section of the drum interior, a sealing strip of resilient material adhered to the inner surface of the drum which cooperates with the adjustable partition to seal off the space between the drum end and the adjustable partition, means for moving the adjustable partition back and forth within the drum interior, and means through which a heating medium is introduced within the drum interior at a point beyond the sealed off section of the drum interior.

11. A drying roll for drying a continuously traveling

sheet of flexible material comprising a rotatable hollow drum having a substantially smooth and uninterrupted surface over and against which the sheet travels, hollow end supports for the drum, an adjustable partition within the drum which is rotatable therewith for sealing off a section of the drum interior, a resilient sponge rubber ring positioned around the adjustable partition, means for retaining the sponge strip in position on the partition, means for adjusting and controlling the position of the partition within the drum interior and means through which a heating medium is introduced within the drum interior at a point beyond the sealed off section of the drum interior.

12. A drying roll for drying a continuously traveling sheet of flexible material comprising a drum, hollow end supports for the drum, a first adjustable partition within the drum, a second adjustable partition within the drum, a sleeve assembly secured to the second adjustable partition, said sleeve assembly extending through an end support to a point beyond the end support, a hand grip affixed to the free end of the sleeve assembly, a pipe extending through the sleeve assembly to a point beyond the adjustable partition for supplying a heating medium between the partitions, and a heating medium exhaust channel defined by the bore of the sleeve assembly and the periphery of the feed pipe.
